Primary Examiner — Paula Allen Greene(57) **CLAIM**

The ornamental design for an earphone, as shown and described.

DESCRIPTION

FIG. 1 is a top, front and right side perspective view of an earphone showing our new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and right side perspective view of the earphone with an earplug cap; and,

FIG. 10 is a bottom, rear and left side perspective view of the earphone with an earplug cap.

The broken lines in the drawing illustrate portions of the earphone in FIGS. 1 through 8 and earphone earplug cap in FIGS. 9 and 10 that form no part of the claimed design.
